UNITED STATES PATENT OFFICE.

FRITZ DÜRR, OF HEIDELBERG, GERMANY.

CARBURETER.

1,081,222.

Specification of Letters Patent.

Patented Dec. 9, 1913.

Application filed August 29, 1912. Serial No. 717,767.

To all whom it may concern:

Be it known that I, FRITZ DÜRR, a subject of the German Emperor, and resident of Heidelberg, Germany, have invented certain new and useful Improvements in Carbureters, of which the following is a specification.

In order to form a carbureter of a great efficiency, of reduced dimensions and of simple construction, the fuel flows upward according to the present invention in a straight line through the axial bore of a centrally disposed tube the remaining parts or organs of the carbureter being arranged 15 symmetrically and concentrically with respect to said straight fuel conveying tube.

The arrangement is such that the jet of fuel, centrally entering the spraying nozzle, is first broken or divided by eccentrically 20 directed air jets and afterward given a rotary motion. In this manner not only a thorough pulverization of the fuel, but also an intimate mixing of the fuel with air is secured. Furthermore the regulating is 25 performed in such a manner that the amount of fuel is proportionate to the amount of air.

The invention is shown in the accompanying drawing in which:

80 Figure 1 is a longitudinal section of the carbureter. Fig. 2 is a horizontal section on line II—II of Fig. 1. Fig. 3 is a top view of the carbureter valve.

The carbureter comprises a casing 1 the upper open end of which is threaded at 2 for securing the carbureter to the suction pipe of the motor. The lower end of the casing 1 is closed and centrally provided with a pipe 3 conveying the fuel to the carbureter. Said pipe is centrally bored. Into the upper, large bore is engaged a spindle 4 which is provided at its lower end with a reduced portion and a conical extension. This reduced portion of the spindle forms 45 with the bore of the piping 3 a chamber 5 while the conical end of the spindle, according to its position, closes or opens the duct 6. The spindle 4 is centrally bored at 7, said bore terminating in a nozzle 8 while the opposite end communicates by 50 means of bores 9 with the chamber 5. With the spindle 4 is connected a piston 10 which is guided by the lower part of the carbureter 1. This piston is under the action of a spring 11 one end of which bears against 55 the piston 10 while the other end bears

against a projection of the rotating valve 12. This valve 12 is rotatably mounted by means of a threaded portion within the carbureter and may be rotated by means of a handle 13. Furthermore apertures 14 are provided in the rotating valve 12, said apertures corresponding with apertures 15 of the same size provided in the carbureter casting 1, thus establishing a connection between the space above the piston and the outer air. The space below the piston 10 communicates on one side through the duct 16 with the outer air and on the other hand, by means of the ducts 17, with the nozzle 8. Said ducts, according to Fig. 3, are positioned with respect to each other in such a manner that the outer edges cross the central axis of the nozzle and consequently of the jet of fuel. If the air, flowing with a certain velocity through said ducts 17, meets the jet of fuel, the latter is broken and caused to whirl, thus producing not only a thorough spraying of the fuel, but also an intimate and perfect mixture of the fuel with the air.

The fuel is supplied to the duct 6 from a reservoir by means of a pipe which is screwed at one end to the reservoir, at the other end to the duct 6. A usual valve 85 is provided on said pipe for controlling the flow of fuel as desired, and the height of the reservoir above the nozzle 8 is such that the pressure of the fuel in the duct 6 does not become greater than the pressure (weight) 90 of the valve 4, together with the pressure of the spring 11.

When the motor is sucking, a depression is produced about the piston 10, which piston is raised together with the spindle 4, 95 so that fuel flows through the bore 6 into the chamber 5 and from this chamber through the duct 7 to the nozzle 8. The jet of fuel is then pulverized by means of the air flowing through the ducts 17 as above stated. To this pulverized mixture saturated with fuel atmospheric air is conveyed through the apertures 15 and 16. The amount of conveyed air is regulated by rotating the valve 12. As this valve is also moving in the direction of its axis, the distance between the air piston 10 and the valve 12 varies. The arrangement is such that if the aperture 15 is closed, that is to say if no more air enters, the valve 12 is resting upon the air piston 10 and closes the fuel conveying duct. According to the amount of air, which amount

2
is regulated by the position of the valve, more or less fuel is conveyed. By these means a constant proportion of the mixture elements may be got, whatever may be the 5 amount of conveyed air, which arrangement dispenses with a throttle valve between the carbureter and the motor.

Having now fully described my said invention, what I claim and desire to secure 10 by Letters Patent is:

1. In a carbureter, the combination of a casing formed with air inlet openings, a spraying nozzle vertically and centrally disposed in the casing, a valve for controlling 15 the openings in the casing, a spring interposed between the valve and the nozzle, means for admitting a supply of liquid fuel and air to the nozzle, means for operating the valve to close the openings and prevent 20 operation of the nozzle, including screw threads between the casing and the valve, and a handle extending from the valve.

2. In a carbureter, the combination of a casing formed with air inlet openings, a 25 vertical seat and an opening in the bottom of the latter, a vertically movable element having a flanged portion which operates in the casing, and a centrally disposed stem which operates in the seat, the stem having 30 a reduced portion at its end to normally close the bottom opening, said stem having a duct which extends through from near the bottom to the top of the element, the duct being flared at its upper end, the stem having 35 inclined air inlet openings which com-

municate with the flared portion of the duct and a space formed between the element and the casing, the casing having an air inlet port for the passage of air to said space, a valve for controlling the admission of air to 40 the casing, and resilient means for holding the element down to normally close the bottom opening in the bottom of the seat.

3. In a carbureter, the combination of a casing, a vertical extension in the bottom of the casing formed in its bottom with a fuel inlet opening, a circular conical shell having a central vertical stem reduced at its lower end to normally close the fuel inlet opening, said stem having an opening extending from 45 the bottom to the top of the stem and shell, the upper end of the opening flaring outwardly, the stem having inclined openings below the top of the shell and communicating with the flared portion of the opening, 50 the outlets of the inclined openings being disposed out of alignment with each other to whirl the fluid passing through the opening to the casing, the casing having an opening for the admission of air to the inclined openings in the stem, and a spring acting on the shell for normally closing the fuel inlet opening.

In testimony whereof I have hereunto set my hand in presence of two witnesses.

FRITZ DÜRR.
